LUBRICATING MEANS FOR BEARINGS

Victor Alexander Bary, London, England, assignor to Walter Peyinghaus, trading as Eisen- und Stahlwerk Walter Peyinghaus, Egge, near Volmarstein, Ruhr, Germany

Application July 9, 1934, Serial No. 734,298
In Germany July 17, 1933

1 Claim. (Cl. 308—86)

This invention relates to axle bearings for rail vehicles with mechanical feed of the lubricant by a feeding member rotating with the axle journal. This feeding member consists in the usual manner of a feed rod to which feed blades are attached. According to the present invention, the feeding member comprises a rod-shaped center piece with feed blades arranged thereon, the feed blades having the shape of segments of a ring and enlarged in the form of a T over the width of the rod-shaped center piece. The inner edge of the feed blades, which faces the axis of rotation, extends over the feed rod in a length corresponding to at least one half of the width of the feed rod, and the inner edges of the feed blade, which extend over the feed rod, have with increasing distance from the center of the feed blade a decreasing distance from the axis of rotation.

Feeding members designed according to the invention have the special advantage that owing to the peculiar shape or form of the feed blade, the lubricant taken up by the feed blade during its passage through the store of lubricant reaches the inner edge of the feed blade when the feed blade has reached the highest point of its path of rotation and is located above the collecting member for the lubricant. This collecting member is usually formed from a projection of the bearing brass around which the feed rod is bent. This collecting member is therefore reached by the lubricant with certainty because owing to the peculiar course of the inner edge of the feed blade extending over the feed rod a component of the force of gravity acting on the lubricant draws the lubricant toward the lower corner points of the feed blade. The lubricant is thereby accumulated at points on the inner edge of the feed blade and the force of gravity of this accumulation at points is adapted to overcome the adhesion and cohesion forces with certainty and ease although the latter forces are known to be very high in connection with the lubricant. In the case of low speeds, the lubricant must drip down with certainty and thereby reach the oil collecting member in the uppermost point of the path of rotation. The delivered amounts of lubricant are comparatively large because the T-shaped enlarged feed blade has a comparatively large surface whereby lubricant can be taken up to an adequate extent.

The bend of the feed rod may be, as shown, a less distance from the axis of rotation than the inner edge of the feed blade facing the axis

of rotation so that an agitation of the store of lubricant during the passage of the feed blade is completely avoided. The feed blade may be kept very thin and provided with sharpened edges. However, the feed rod must be comparatively strong to take up the centrifugal forces of the feed blade so that should it pass through the store of lubricant it produces a strong emulsification, oxidation and premature aging of the lubricant. The passage of the feed rod through the store of lubricant was hitherto unavoidable if the whole feed blade had to dip into the store of lubricant. According to the present invention, the dipping of the whole feed blade is effected without it being necessary for the feed rod to dip into the store of lubricant.

If the feed blades are constructed as polygons and the arrangement of the corner points of the polygons differs according to the different feed blades, there results therefrom the advantageous feature that the feed blades cannot assume at certain speed of the axle journal critical states of equilibrium to which the feed of the lubricant is subjected. These critical states of equilibrium are produced by the fact that the forces causing the separation of the lubricant and keeping it against the feed blade can maintain an equilibrium at certain velocities of rotation of the feed blade because centrifugal force is dependent on the velocity of rotation. Owing to the different relative positions of the corner points, the bounding edges of the feed blades have a different distance from the center of rotation and a different length so that the centrifugal forces are never the same at these bounding edges. The critical conditions of equilibrium cannot occur at the same time in connection with both the feed blades.

In order to give the feed blades the correct size, it is advantageous to provide a constant ratio between the effective feed-blade face and the axle-journal surface independently of the axle-journal diameter. The surprising fact results therefrom that when keeping this ratio constant the bearing surface always receives the lubricant which is required for an adequate lubrication.

The drawings show by way of example the construction of an oil feed-rod formed according to the invention,

Fig. 1 showing a side elevation of the oil feed rod, while

Fig. 2 represents a front elevation of the same.

Fig. 3 shows in vertical longitudinal section

through an axle-bearing the arrangement of the blade according to Figs. 1-2.

The oil feed rod is according to the invention characterized by the feature that the distance of the inner edges 7', 8', 9' and 10' of each of the two feed blades 1, 2 from the axis of rotation is smaller the greater the distance from the centre of the feed blade. In other words the distance of the inner edges of the feed blades from the axis of rotation is gradually reduced toward the inner apices 18, 19 and 20, 21 so that these apices are located closer to the axis of rotation than the remaining portion of the edges of the blades. Incidentally the outer edges of the blades are situated on the same arc with respect to the axis of rotation. Moreover the distance of any radial line drawn from the inner edge to the outer edge of each blade is only approximately one-half of the width of the rod support 13. The feed blades are consequently cut back in the direction of rotation at 3, 4, 5 and 6 drip-tips 7, 8, 9 and 10 being formed, and the surface of the feed blade being perpendicular to the rod-face 11, 12 supporting the feed blade. The rod-support 13 itself, which may be firmly connected by way of holes 14 with the axle journal which is not illustrated, possesses at 15 and 16 outwardly arched portions which enable a catching member, which is shown in Fig. 3, to be located within range of the drippings and threads formed by the feed-member. As is noticeable particularly from the lower parts of Figs. 1 and 2, the whole of the feed blades 1 and 2 together with the drip-tips 7-10 can consequently be dipped into the lubricant store 17 without the parts 11 and 12 of the rod-support, that is the rod-support 13 as such, requiring to dip into the lubricant store. Nevertheless fully developed drip-tips are formed, which cause the lubricant to drip off with certainty. The lubricant store is consequently traversed only by the feed blades, without it being possible for the lubricant store to be injuriously lashed up, emulsified and oxidized.

As is also noticeable from Figs. 1 and 2, the bounding edges 7', 7'', 8', 8'', 9', 9'' and 10', 10'' which form the drip-tips, possess different lengths on the different feed blades. The result of this is that the mutual action between gravity, forces of adhesion, forces of cohesion and centrifugal forces, in so far as they interact to bring about the dripping of the lubricant, take place differently on the two feed blades, so that always one feed blade effects dripping with certainty when in the case of the other feed blade certain conditions of equilibrium of the said forces have already occurred, the dripping during this time being discontinued. It is also noticeable that the feed blades are constructed as polygons which differ from one another as regards the positions of their apices, so that in particular the position of the apices 18, 19 of the feed blade 1 giving rise to the formation of threads is different from the position of the apices 20, 21 in the case of the other feed blade. Consequently the threads formed by the feed blades cannot mutually disturb one another. Finally, the bounding edges 22, 23, of the feed blades 1 and 2, which edges act centrifugally, possess different lengths, so that

the resultant forces which lead to the centrifuging of the lubricant arise in the case of the two feed blades in such a different way that one feed blade throws off the lubricant before the other feed blade throws it off. 5

Finally, Figs. 1 and 2 show that the feed blades are constructed as narrow segments of a ring, so that the paths along which the lubricant slips, measured in the radial direction, are shorter than the paths, along which it is drawn, measured in the peripheral direction. This is worthy of consideration in so far as in consequence of forces of inertia arising in the case of an insufficient ratio between the paths along which the lubricant is drawn and those along which it slips the lubricant is discharged from the feed blades before the latter have reached their position above the collecting member; the lubricant consequently passes back unused into the lubricant store, while lubricant is supplied insufficiently to the bearing surface. Fig. 2 shows that the realization of a satisfactory relationship is possible without the fulfilment of the other requirements being disturbed. 20

The edges 7', 7'', 8', 8'', 9', 9'', 10', 10'', 22 and 23 are formed as knife-edges in a manner well known per se, in order to prevent air from being driven into the lubricant store. 25

The feature that the moistened surface of the feed blades may have a constant ratio to the surface of the axle-journal, independently of the diameter of the axle-journal, lies within the scope of the invention. By means of this feature the supply of the requisite sufficient quantity of lubricant to the bearing surface is always 35 accomplished without troublesome testing of rod-shaped feed members of different sizes being necessary. 30

The principle of the invention is also realized when the faces of the rod-support carrying the feed blades are not perpendicular to the face of the feed blade but are at an oblique angle to the same. With this arrangement, however, there is connected the disadvantage that when the outermost diameter is given the face of the feed blade is unnecessarily small; it might, without the support having to dip into the store of lubricant, be increased by the amount in question, if the supporting face of the rod were positioned at right angles to the face of the feed blade. 40 45 50

I claim:

An axle bearing comprising an axle box housing, a bearing brass adapted to receive an axle journal, a lubricant store in said housing, feeding means adapted to lift lubricant from said lubricant store, said feeding means comprising a rod-shaped center piece, feed blades on said center piece, said feed blades designed as segments of a ring and extending T-shaped across the rod-shaped center piece of said feeding means, a collecting member for the lubricant in the annular space swept over by the said feed blades during the rotation of the feeding means, said rod-shaped center piece bent around said collecting member, said bend being at a shorter distance 60 from the axis of rotation than the inner edge of the feed blades facing the axis of rotation. 55 65
